UNITED STATES PATENT OFFICE.

EDISON G. HULSE, OF AKRON, OHIO, ASSIGNOR TO KELLY-SPRINGFIELD TIRE COMPANY.
OF JERSEY CITY, NEW JERSEY, A CORPORATION OF NEW JERSEY.

MACHINE FOR MAKING PNEUMATIC-TIRE FLAPS.

1,302,660.

Specification of Letters Patent.

Patented May 6, 1919.

Application filed October 18, 1917. Serial No. 197,239.

To all whom it may concern:

Be it known that I, EDISON G. HULSE, a citizen of the United States, residing at Akron, in the county of Summit and State of Ohio, have invented certain new and useful Improvements in Machines for Making Pneumatic-Tire Flaps, of which the following is a specification.

This invention relates to improvements in machines for making flaps for pneumatic tires.

The object of the invention is to provide a machine of simple construction which will be effective in operation and capable of being easily manipulated.

In the accompanying drawings:

Figure 1 is a top plan view partly broken away.

Fig. 2 is a side elevation.

Fig. 3 is an end view.

Fig. 4 is a top plan view of the turn-over device.

Fig. 5 is an end view of the same.

Fig. 6 is a section of the flap as it is fed to the compression rolls.

It is usual to provide a pneumatic tire with a flap which is placed in the casing so as to close the space between the beads for the purpose of furnishing a smooth seat for the inner tube.

These tire flaps are made up of layers of rubberized fabric of different widths so disposed that the flap will be the thickest in the center and of a slightly concavo-convex shape so that it will conform to the shape of the casing and inner tube.

Referring to the drawings, 1 represents a supporting base or platform arranged at the upper ends of legs 2, which may be strengthened by cross pieces 3 so as to provide a suitable supporting frame for the operating parts of the machine.

The rolls of rubberized fabric are mounted upon an upright support 4 at the forward end of the machine, 5 representing what is known as the cover strip, and 6, 7, 8 and 9 the intermediate strips, these rolls being placed upon wooden pegs 10 which project laterally from the support 4. There is also provided what is known as a base strip 11, this base strip being preferably of flannel rubberized on the upper side, this roll 11 being placed upon a peg 12 projecting laterally from a support 13, with a flexible band 14 having a weight 15 hung about the same

so as to provide the necessary tension. Leading from the various rolls is a series of supports 17, 18, 19, 20, 21 and 22, converged rearwardly so that their rear ends will be in close proximity to each other, the rear ends being secured to an upright support 23. These supports preferably have guide strips S on the back edge thereof and not only serve the purpose of guiding the strips of rubberized fabric, but also provide a convenient arrangement for splicing the end of a new roll of fabric to the end of the exhausted roll, the operator stopping the machine for this purpose in the manner hereinafter explained. From the supports the strips of fabric pass through suitable guides 24, 25 and 26 having aligned apertures of decreasing height so that the strips will be brought in close proximity to each other, and from these guides the series of fabric strips pass into a turnover device.

It should be explained that the roll 11 is of greater width than the others so that its edges will project beyond the same; the roll 5, which is the cover strip, being of the same width as the finished flap; the intermediate strips being of varying widths, as shown in Fig. 6. The turn-over device referred to is for the purpose of turning over the edges of the base strip 11 and is shown in detail in Figs. 4 and 5. This turn over device is in the nature of a plate 27 having its side edges 27^a bent upwardly and inwardly so as to form groove-ways which converge rearwardly; the distance between the side walls of the groove-ways at the forward end of the plate 27 being substantially the same as the width of the strip 11 and the distance between the walls of the groove-ways at the rear end of the plate being substantially the width of the flap as finally formed. As the series of layers enter this turn-over device, therefore, it will be seen that the edges of the strip 11 are turned over to the position shown in Fig. 6. From the turn-over device the series of strips pass through two compression rolls 28 and 29, the lower roll 29 having a straight periphery and the upper roll 28 a concave periphery to conform to the varying thickness of the fabric strips. Springs 30 serve to hold these rolls yieldably together so as to put a yielding pressure upon the strips to cause them to adhere together, adjusting screws 31 being provided to adjust the tension of the springs.

- From the pressure rolls 28 and 29 the series of strips pass through a pair of pressure and driving rolls 32 and 33, which are driven in the manner hereinafter explained, and also with these rolls the lower one is formed with a straight periphery and the upper one with a concaved periphery to conform to the varying thickness of the flap. Adjusting screws 34 are provided for holding these rolls together to the necessary extent to place a proper pressure upon the fabric strips for driving purposes.
- From these rolls 32 and 33 the flap thus formed is rolled upon a reel 35 which may be readily removed when filled, and taken to the vulcanizing mold, where the flap is cured and given the concavo-convex form previously referred to. This reel is rotated in the manner now explained.
- In the present case there is shown an electric motor 36 mounted upon a suitable support 37 on the frame which drives a counter-shaft 38, mounted in suitable bearings 39 at the rear end of the frame, the driving connection being through the medium of the pulleys 40 and 41 and belt 42. The counter-shaft 38 has a smaller pulley 43 which drives a pulley 44 by a belt 45 the pulley 44 being secured to a shaft 46 mounted in suitable bearings 47 secured to and depending from the table 1. This shaft 46 has a sprocket wheel 48 which transmits motion to the sprocket wheel 49 on the shaft of the roll 33 through the medium of the sprocket chain 50, the roll 32 being driven from the roll 33 by the gears 32^a and 33^a. The shaft of the roll 33 has a pulley 51 and the shaft of the reel 35 has a pulley 52 whereby motion is transmitted to the reel through the medium of a belt 53.
- For the purpose of starting and stopping the machine there is provided a hand lever 54 which is connected to a crank arm 55 by a rod 56 the crank arm being attached to a transverse shaft 57 which has a second crank arm 58 provided with an idle pulley 59 over which passes the belt 45 so that the belt may be loosened or tightened.
- Having thus described my invention, I claim:—
1. In a machine of the character described, supports for a series of fabric rolls, devices associated therewith for causing fabric strips to be drawn therefrom and laid together, supporting table-like guides between said rolls and said devices converging toward said devices, and means for compressing said strips to cause them to adhere together.
  2. In a machine of the character described, supports for a series of fabric rolls, a series of flat table-like supporting guides for said rolls converging rearwardly, a turn-over device, compressing rolls, and feeding rolls.
  3. In a machine of the character described, supports for a series of fabric rolls arranged in substantially vertical alinement, a series of flat guiding supports for the fabric from said rolls converging rearwardly, apertured auxiliary guides for the fabric strips, a turn-over device, a pair of compressing rolls, and a pair of feed rolls.
  4. In a machine of the character described, supports for a series of fabric rolls arranged in substantially vertical alinement, a series of flat guiding supports for the fabric from said rolls converging rearwardly, apertured auxiliary guides for the fabric strips, a turn-over device, a pair of compressing rolls, a pair of feed rolls, and a drum to receive the fabric strips.

In testimony whereof, I have hereunto set my hand this 1st day of October, 1917.

EDISON G. HULSE.
